UNITED STATES PATENT OFFICE.

JOHN L. WILCOX, OF SEATTLE, WASHINGTON.

HAND-SCRAPER.

1,205,121.

Specification of Letters Patent.

Patented Nov. 14, 1916.

Application filed April 8, 1916. Serial No. 89,892.

To all whom it may concern:

Be it known that I, JOHN L. WILCOX, a citizen of the United States, residing at Seattle, in the county of King and State 5 of Washington, have invented certain new and useful Improvements in Hand-Scrapers, of which the following is a specification.

This invention relates to improvements in a tool designed primarily to scrape wood 10 before finishing.

The object of the invention is to provide an elongated tool, the body portion of which constitutes a handle, and a means for holding and clamping a blade in the free 15 end.

The invention also comprehends improvements in the details of construction and arrangement of parts which will be herein-after described and particularly pointed out 20 in the claim.

In the drawing, Figure 1 is a perspective view of my improved scraper. Fig. 2 is a central vertical section of the same. Fig. 3 is a transverse section on the line $\alpha-\alpha$ of 25 Fig. 2.

The same numerals refer to like parts in all the figures.

1 indicates a body portion, preferably of wood, the rear end of which is shaped to 30 form a convenient grip 2, while the opposite end is formed with a horizontal slit, indicated at 3, to provide upper and lower clamping jaws 4 and 5. The free ends of the jaws 4 and 5 are beveled, as shown at 6, 35 the purpose of which will be obvious.

Below the body portion and adjacent the rear end of the slit 3, is a transverse groove 5^a, and above the same and formed in the upper surface of said body portion is a 40 transverse slit 6. The slit 6 acts to weaken the wood and to form a fulcrum for the upper jaw 4, for a purpose to be described.

Seated in the groove 5^a, is the horizontal portion 7, of a yoke 8, the vertical portions 45 9, thereof, extending upwardly beyond the upper surface of the body portion, and are connected by a rod 10. Fitting under the rod 10, and extending beyond and behind same, is a clamp 11, the front end of which 50 engages the top surface of the jaw 4, at a point intermediate the free end thereof, and the slit 6. In the rear end of the clamp is a threaded opening 12, in which engages a thumb screw 13, the end of which engages 55 the top surface of the handle portion.

To properly position the clamp with ref-

erence to the rod 10, the clamp is formed with shoulders 14, hence when assembling the parts, the clamp can be quickly positioned.

A flat scraper blade is fitted in the slit 3, its rear end abutting against the rear wall of the slit to insure stability when the tool is used, while the front end of the blade projects beyond the free ends of the jaws, 65 as shown.

In use, the blade is placed in the slit, and the rear edges are engaged by the vertical portions 9, of the yoke, to prevent lateral movement, while, as previously stated, the 70 rear edge of the blade abuts against the rear wall of the slit. The blade therefore is held rigid, longitudinally with the body portion, and is also held against lateral movement when the clamp is operated.

The blade having been properly positioned, the thumb screw 13, is adjusted, because of the rod 10, acting as a fulcrum, the front end of the clamp bears on the upper jaw 4, and bends same toward the 80 jaw 5, and effectually clamps the blade between said jaws. The slit 6, readily permits of the jaw 4 yielding sufficiently under the pressure exerted by the forward end of the clamp. As the movement necessary to 85 accomplish the desired result is but slight, obviously liability of the body portion breaking at the fulcrum point is remote.

The action incident to exerting pressure on the jaw 4, by the clamp, the yoke 8 is 90 drawn up tight against the body portion, and as the rear end of the blade is confined by said yoke, it is also clamped tight at this point.

To release the blade it is only necessary 95 to release the thumb screw, which releases the yoke and the clamp, with the result that upper jaw 4, assumes its normal position and the blade can be withdrawn.

By the construction described I have provided a simple scraper construction, and one which can be economically made. The body portion comprising the handle and the blade holder permits of the use of a single piece of material, and also permits of the 100 use of a simple and inexpensive clamping means.

What I claim is:—

A hand scraper comprising a straight wooden body portion shaped at one end to 110 provide a handle and having a horizontal slit at its opposite end to provide a pair of

jaws, the upper surface of the body portion adjacent the rear end of the slit having a transverse slit, a blade fitted in the horizontal slit and abutting against the rear wall of the latter, and blade holding means including a clamp, one end of which engages the surface of the upper jaw in front of the transverse slit, and a screw at the opposite end of the clamp and engaging the

upper surface of the handle to cause the front end to bend the upper jaw and clamp the blade in position in the horizontal slit.

In testimony whereof I affix my signature in the presence of two witnesses.

JOHN L. WILCOX.
